OTHER PUBLICATIONS

Mar. 14, 2016, Office action from the U.S. Patent and Trademark Office in U.S. Appl. No. 29/498,615, which is another application of Applicant Chinook Asia LLC.

Primary Examiner — T. Chase Nelson(74) *Attorney, Agent, or Firm* — Kolisch Hartwell, P.C.(57) **CLAIM**

The ornamental design for a shoe outsole, as shown and described.

DESCRIPTION

FIG. 1 is a front and left side perspective view of a shoe outsole showing my new design;

FIG. 2 is a front elevational view thereof;

FIG. 3 is a rear elevational view thereof;

FIG. 4 is right side elevational view thereof;

FIG. 5 is a left side elevational view thereof;

FIG. 6 is a top plan view thereof;

FIG. 7 is a bottom plan view thereof; and,

FIG. 8 is a bottom perspective view thereof.

The dashed lines shown in the drawings are included for illustrative purposes only and form no part of the claimed design.
